UNITED STATES PATENT OFFICE

VARDAMAN G. WILKINS, OF SILVER CITY, IOWA

WIRE SPLICER

Application filed January 26, 1931. Serial No. 511,341.

This invention relates to a wire splicer and its primary object is to facilitate the repairing of broken line wires of fences.

A still further object of the invention is to provide a device of this nature to which the ends of the broken wire may be secured and retained in overlapping relation in such a manner that the overlapping ends of the wire may be twisted together for securing said ends together.

A still further object of the invention is to provide a device of this character which is simple in construction, comprises comparatively few parts, is thoroughly reliable, practical and efficient in operation and otherwise well adapted for the purpose designed.

Other objects and advantages of the invention will become apparent during a study of the following description, taken in connection with the accompanying drawings, wherein:

Figure 1 is a side elevational view of my improved wire splicer, the same being shown associated with the end of the broken line wire,

Figure 2 is an edge elevation thereof,

Figure 3 is a detail view partly in section and partly in elevation taken substantially on the line 3-3 of Figure 1,

Figure 4 is a view similar to Figure 1 and showing the manner of twisting of the wire when using the wire splicer,

Figure 5 is a detail sectional elevational view similar to Figure 3, the jaws of the clamp being closed,

Figure 6 is a plan view of a twisting tool.

With reference more in detail to the drawings, it will be seen that my improved wire splicer comprises an elongated rectangular plate 5 formed of metal or any other suitable material which will be light yet strong and durable.

The plate 5 at one end thereof is provided with an elongated notch 6 opening inwardly from one end of the plate. Journalled in said end of the body plate 5 is a rotatable shaft 7, which shaft extends transversely of the notch 6.

At one end, the shaft 7 terminates in a suitable crank arm or handle 8. To that por-

tion of the shaft 7 extending through the notch 6 and operable within the notch 6 is a ratchet wheel 9. A dog 10 has one end thereof pivotally mounted between spaced ears 11 as at 12 which ears 11-11 project laterally from one side of the plate 5.

The free end of the dog 10 is adapted to engage the teeth of the ratchet wheel 9 for locking the shaft 7 against rotative movement in one direction when desired.

On the free end of the shaft 7 and mounted thereon for rotation therewith in any suitable manner is a cylindrical stub post 13, and this stub post 13 at its upper end has projecting laterally therefrom headed stud 14.

At right angles to the plate 5, and extending from the same side of the plate as the extended end of the shaft 7 are a pair of wire engaging clamps each designated generally by the reference character C.

These wire engaging clamps as illustrated are identical in construction, each of the clamps comprising a cylindrical shank portion 14 extending laterally from the said one longitudinal edge of the plate 5, said shank portion 14 terminating in a substantially C shaped jaw 15. The jaw 15 constitutes the stationary jaw of the clamps.

A similarly shaped jaw 16 cooperates with the jaw 15 to provide a retaining loop therebetween, and this jaw 16 at one end thereof is pivoted as at 17 to the shank 14 at the junction of the shank and jaw 15.

For yieldably retaining the cooperative jaws 15 and 16 in closed position, that is in a loop forming position there is provided a washer or annulus 18 slidable on the shank 14, and a coil spring 19 is convoluted about said shank, one end of the coil spring bearing against the adjacent edge portion of the plate 5, and the other end of said coil spring impinging against the washer 18 for urging the washer 18 upwardly to engage with the pivoted end portion of movable jaw 16 for urging said movable jaw into loop forming position with the stationary jaw 15 shown to advantage in Figure 1.

In actual practice, the jaws of the clamps C-C are in normally closed or loop forming position and one end α of the broken line wire

of the fence is trained through the loops so formed of each of the clamps and the free end portion of the wire end *a* is then twisted or wrapped about the headed lug 14 on the post 13.

The opposite end *b* of the broken line wire is also trained through the registering loops of clamps C—C and the terminal of the wire end *b* is twisted about the headed stud 19 projecting from one side of the plate 5 at that end of the plate 5 remote from the notch 6.

Manifestly, by rotating the shaft 7, in a suitable direction, the end portion *a* of the line wire will be wrapped around the stub post 13 and in this manner the line wire will be drawn taut as is apparent.

From a study of Figure 1, it will be seen that those portions of the ends *a* and *b* of the line wire extending between the clamps 20 C are in spaced parallel relation and for securing the ends *a* and *b* together, the parallel portions of the ends *a* and *b* are twisted together in the following manner: Any suitable tool such as that designated generally 25 by the reference character T as shown in Figure 6 may be utilized for this purpose, the shank 20 of which tool being placed between the wires and obviously by rotating the tool T, the ends *a* and *b* will be suitably 30 twisted one with the other and in this manner the ends *a* and *b* suitably secured together.

The ends of the wire having been so connected, to remove the tool, the terminals of 35 the ends *a* and *b* may be unwrapped from about the studs 14 and 19 respectively and the rings or washers moved out of engagement with the pivoted jaws of the clamp members to permit spreading of the jaws 40 and subsequent removal of the tool.

Manifestly, when the end *a* of the wire has been suitably wound upon the sub-shaft 13 for drawing the wire line tight or sufficiently taut, the shaft 7 during the twisting 45 of the ends of the wire together will be held against rotation in an opposite direction through the medium of the pivoted dog 10 having its free end engaging the teeth of the ratchet wheel 9 as is apparent.

It is thought that from the foregoing description, taken in connection with the accompanying drawings, a clear understanding of the operation, construction, utility and advantages of a wire splicer of this 55 character will be had by those skilled in the art without a more detailed description.

Even though I have herein shown and described the preferred embodiment of my invention, it is to be understood that the same 60 is susceptible to certain changes comprehended by the spirit of the invention as herein described, and the scope of the appended claims.

Having thus described my invention, what I claim as new is:

1. In a wire splicer of the class described, a body member, a shaft rotatably mounted on said body member adjacent one end thereof, said shaft being provided on one end thereof with an operating handle, and the 70 other end of said shaft extending laterally from said body member, means on the extended end of said shaft for securing one end of a line wire thereto, means for retaining said shaft against rotation in one direction, said body member having a headed stud projecting from one side thereof to which is adapted to be secured a second end of the line wire, said stud being mounted on said body member at the opposite end of said body member whereby the ends of the line wire may be retained in overlapping relation 80 so that a tool inserted between the overlapping ends of the line wire may be rotated for twisting said ends together.

2. In a wire splicer of the class described, an elongated rectangular body member, having an elongated notch extending inwardly from one end thereof, a shaft extending through said one end of said body member transversely thereof, said shaft being rotatable, a ratchet wheel fixed to the intermediate portion of said shaft for rotation therewith within said notch, a dog pivotally mounted on one side of said body member and engaging the teeth of said ratchet wheel, means for securing one end of a broken line wire to one end of said shaft for winding said one end of said wire about said shaft, said shaft at its opposite end being provided with an operating handle, loop members on said body member at one longitudinal edge of said body member and through which members are trained the ends of the broken line wire, means for securing the terminal 100 of the other end of the line wire to said body member at that end thereof remote from said shaft, whereby the portions of the broken line wire extending through said loop members may be readily twisted together.

3. In a wire splicer of the class described, an elongated rectangular body portion, having an elongated notch extending inwardly from one end thereof, a shaft extending through said one end of said body portion transversely thereof, said shaft being rotatable, a ratchet wheel fixed to the intermediate portion of said shaft for rotation therewith within said notch, a dog pivotally mounted on one side of said body portion and engaging the teeth of said ratchet wheel, means for securing one end of a broken line wire to one end of said shaft for winding said one end of said wire about said shaft, said shaft at its opposite end being provided with an operating handle, loop members on said body portion at one longitudinal edge thereof and through which members are trained the end of the broken line wire, means for securing the terminal 110 of the other end of the line wire 120 125 130

to said body portion at that end thereof remote from said shaft, whereby the portions of the broken line wire extending through said loop members may be readily twisted together, each of said loop members comprising a stationary jaw and a pivoted jaw, and means normally urging the pivoted jaw into cooperative position with the stationary jaw to form a loop.

4. In a wire splicer of the class described, an elongated rectangular plate provided with an aperture, a transverse shaft rotatably mounted on the plate, a ratchet wheel on the shaft within said aperture, a dog pivotally mounted on the plate and engaging the ratchet wheel to retain the shaft against retrograde movement, a wire anchor member on the plate remote from the shaft, and a lined expansible loop members projecting laterally from said plate.

5. A device of the character described comprising a plate-like body provided at one end with fixed means for securing one end of a wire thereto, a shaft rotatably mounted on the plate and adapted to have a second end of a wire wound thereon, and a lined loop members adjacent one edge of the plate through which the referred to ends of the wire extend in substantial parallelism.

6. A device of the character described comprising in combination, a body member provided with relatively spaced wire anchor means, and clamps mounted on the body member, each of said clamps comprising a pair of co-acting jaws adapted to receive therebetween portions of the wire ends anchored to said body.

7. A device of the character described comprising in combination a body member provided with relatively spaced wire anchoring means so relatively arranged, as to cause anchored wire ends to extend in substantial parallelism, a loop device and said loop device comprising a fixed jaw, a pivotally mounted jaw co-operative with the fixed jaw, and yieldable means acting on the pivoted jaw for retaining said jaws in clamping relation relative to one another.

8. A device for coupling adjacent ends of a wire together, comprising in combination means engageable with the wire ends for retaining the same in substantial spaced parallelism, and a relatively fixed loop device through which said parallel ends of the wire extend, said loop device comprising a pair of co-operating jaws and a spring device normally retaining said jaws in clamping relation with respect to one another.

9. A device for splicing the ends of a line wire comprising in combination means for securing the spliced ends of the wire in relatively spaced parallelism, and a loop member receiving the parallel portions of the wire, a jaw fixed on the shank, a second jaw co-operative with the first named jaw and pivoted to

the shank, a ring slidable on the shank and engageable with the pivoted jaw and operable to normally retain the jaws in co-operative clamping relation, and a spring member yieldably urging said ring in effective engagement with the pivoted jaw.

In testimony whereof I affix my signature.

VARDAMAN G. WILKINS.
